CAS Semiconductor Wafer, Date Aug. 6, 2020 [online], [retrieved May 30, 2025], <https://www.youtube.com/watch?v=oc5DRA21W1U> (Year: 2020).*Primary Examiner — Sandra Snapp*Assistant Examiner* — Anehita E. Oribabor(74) *Attorney, Agent, or Firm* — Rankin, Hill & Clark LLP(57) **CLAIM**

The ornamental design for a semiconductor wafer heater as shown and described.

DESCRIPTION

FIG. 1 is a perspective view 1 of a semiconductor wafer heater showing our new design

FIG. 2 is a perspective view 2 thereof,

FIG. 3 is a front elevational view thereof,

FIG. 4 is a rear elevational view thereof,

FIG. 5 is a left side elevational view thereof,

FIG. 6 is a right side elevational view thereof,

FIG. 7 is a top plan view thereof,

FIG. 8 is a bottom plan view thereof; and,

FIG. 9 is an end face view taken along line 9-9 thereof.
